2 SHEETS—SHEET 2.

UNITED STATES PATENT OFFICE.

ALLEN E. OSTRANDER, OF RIDGEWOOD, NEW JERSEY, ASSIGNEE TO AMERICAN CAR AND FOUNDRY COMPANY, OF ST. LOUIS, MISSOURI, A CORPORATION OF NEW JERSEY.

TANK-CARRYING BOX-CAR WITH TRUSSSED UNDERFRAME.

1,224,776.

Specification of Letters Patent.

Patented May 1, 1917.

Application filed December 24, 1915. Serial No. 68,586.

To all whom it may concern:

Be it known that I, ALLEN E. OSTRANDER, residing at Ridgewood, Bergen county, New Jersey, and being a citizen of the United States, have invented certain new and useful Improvements in Tank-Carrying Box-Cars with Trussed Underframes, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art. In said drawings—

20 Figure 1 is a longitudinal vertical central section of approximately one-half of the lower portion of the improved tank-carrying box car.

25 Fig. 2 is a composite view, the upper half showing one-half of the longitudinal extent of the underframe and the lower half being a horizontal section somewhat above the floor line, the tank being omitted in both halves.

30 Fig. 3 is another composite view showing on the left a transverse section of the lower half of the car, the section being taken on line 3^a—3^a of Fig. 2, and on the right illustrating another transverse section taken 35 along the line 3—3 of Fig. 2, both as viewed in the direction of the arrows.

Fig. 4 is a transverse section through the underframe and is taken on line 4—4 of Fig. 2 being viewed in the direction of the 40 arrows, and

Fig. 5, is a detailed sectional view taken on line 5—5 Fig. 3.

The invention herein disclosed relates to box cars in which one or more tanks for 45 fluid lading are mounted and inclosed. As the tank or tanks are housed in the box car superstructure the car is adapted to the conveyance of fluids comparatively easily congealed in the winter season. Liquid that 50 is subject to rapid volatilization under the influence of heat may be transported in my improved car. Such liquids will be protected from the heat of the sun during the

warmer seasons of the year and in climates where the temperature is normally excessively great. Due to such protection, dangerous vapor tension will not develop within the tank as would otherwise be the case in connection with some types of inflammable fluid ladings. 55

A meritorious construction is present in the head blocks for the tank which permits a fine adjustment of the head blocks with reference to the tank and prevents to an unusual degree longitudinal shifting of the 65 tank. A bed is provided for each tank and is designed to relieve the thrust of the tank against its head blocks. Simple and efficient means are provided for mounting the head blocks and is readily constructed from 70 commercial material.

Those heavy loads imposed by liquid ladings are amply and uniformly sustained by the strong underframe construction that is provided. The underframe is trussed 75 and the truss rods are ingeniously anchored in the head blocks for the tanks. Struts are employed as queen posts in the trusses and enter into the cross bearer construction in such manner as to contribute to the 80 strength of the underframe to a much greater extent than struts usually do. Other desirable features will become apparent hereinafter and are parts of the present invention. 85

Referring to the drawings, 1 indicates the center sills of the car being shown as commercial channels with their flanges inturned and which extend through and beyond the bolsters. Spliced to the ends of center sills 90 1, and extending to the end sills 2, are channel-shaped draft sills 3. The usual draft gear stops 4 are secured to the inner faces of the draft sills 3, while the outer ends of the draft sills 3 abut the end sills 2, and 95 the latter are cut out for the passage of the draw bar (not shown) of the draft gear. Arranged about the borders of the cut out portion of each end sill 2 is a striking plate casting. 100

The transverse members of the underframe, in addition to the end sills, comprise bolsters 6, cross bearers 7 and floor beams 8 and 8^a, interposed between the bolsters and cross bearers and between successive cross 105 bearers.

Side sills 9, in the form of channels having inwardly extending flanges, are supported by the outer ends of the end sills 2, bolsters 6, cross bearers 7 and floor beams 8 and 8^a. The connection between the terminals of side sills 9 and the end sills 2 is effected by connection angles 10 and horizontally disposed gusset plates 11. (See Fig. 2.)

Bolsters 6 are of the built-up type, as shown in Figs. 2 and 3. Each bolster has a pair of spaced web plates 12, located on each of the opposite sides of the center sills 1, only one half of the bolster being shown in the drawings. The upper and lower edges of each web plate are outlined on their outer faces by top and bottom chords 13 and 14, respectively, both chords being angles.

The vertical edges of the bolster webs are stiffened by other angles, the inner angles 15 serving as connection members between the bolsters and the center sills 1. Outer angles 16 act as connectors between the bolsters and the side sills 9.

Top cover plates 17 span the spaced top chords 13 of the bolster and extend from a line somewhat inset from the top flange of one side sill 9 across the top flanges of the center sills 1 and to a similar line equally removed from the top flange of the side sill 36 on the opposite side of the car. Bottom cover plates 18 extend substantially the entire length of the bottom chords 14 of one pair of bolster webs 12 underneath the bottom flanges of the center sills 1 and along the 35 entire bottom chords 14 of the bolster webs 12 on the opposite side of said center sills.

The usual side bearings 19 are firmly secured to the underside of the bottom cover plates by rivets passing through flanges of 40 the side bearings, bottom cover plate 18 and the outstanding bottom flanges of bottom chords 14. Also secured to the under face of bottom cover plate 18 and between the center sills, is a center bearing plate 20 at each 45 bolster. Having a bottom flange 22 resting upon the upper surface of bottom cover plate 18, between the bottom flanges of the center sills 1, is a bolster center filler provided with a cylindrical socket 21 for the usual king 50 pin. Flange 22 of the bolster center filler is shaped to the upper surface of the bottom flanges of center sills 1 and is upturned to parallel the inner faces of said center sills to form attachment flanges 23. As indicated 55 in Fig. 3 at the right, rivets pass through the flange portion 23 of the center bolster filler, the web of the center sill and through one leg of the connection angle 15. Other rivets pass through the bottom flange 22 of 60 said bolster center filler, the bottom flanges of the center sills and the flange of the center bearing plate 20. Diagonal braces 24 (seen in Fig. 1) are riveted to top cover plates 17 on opposite sides of the center sills 65 and each runs obliquely to one of the gus-

set plates 11 connecting the end and side sills 2 and 9, respectively, being securely riveted to said gusset plate 11. Spaced an appropriate distance rearwardly from each bolster 6, is a floor beam 8, one-half of which is shown in the upper part of Fig. 2. For added clearness, reference may be had to Fig. 4 which illustrates floor beam 8^a, in which, except for intermediate sill 70 and diaphragm 71, similar elements are present. In floor beam 8, however, the web and top and bottom chords extend from the center sills to the side sills, and angles 28 are connected to the center sills. Each floor beam 8 comprises webs 25, one on each side of the center sills each provided with top and bottom chords 26 and 27, respectively, and connection angles 28 securing said web to the web of the center sills 1. Other connection angles 29 secure the outer ends of floor beam webs 25 to the webs of the side sills 9. With its web in alignment with the webs 25 of floor beam 8, is a spacer 30 located between the center sills 1. Said spacer is provided with vertical and horizontal flanges, the former opposing the flanges of the floor beam and center sill connection angles 28 that extend toward the center of the car. Floor beam top and bottom cover plates 31 and 32, respectively, extend nearly from one side 95 sill 9 to the other, crossing the center sills preferably without interruption.

The next spaced transverse underframe member is a cross bearer 7, which, as will hereinafter be made clear, is also part of a strut in the trussed underframe construction. Cross bearers 7 are provided with web plates 33 as illustrated at the left in Fig. 3, each web 33 being provided with top and bottom chords 34 and 35, respectively, in the form of angles. As in the case of the bolster, there is a pair of spaced webs 33 on each side of the center sills and the inner end of said webs are connected to the outer faces of the webs of the center sills 1 by angles 36 which extend below the center sills and are obliquely deflected for a purpose hereinafter set forth. The outer ends of the webs 33 of the cross bearers 7 are connected to the inner faces of side sills 9 by connection angles 37. Both connection angles 36 and 37 also operate as stiffeners for the webs 33 of the cross bearers. Spanning the horizontal flanges of the top chords 34 of cross bearers 7 is a cross bearer top cover plate 38 extending nearly from one side sill 9 to the side sill on the opposite side of the car. Center sill spacers 39 are present at each cross bearer and are located between the center sills so that their web portions are aligned with the webs 33 of the cross bearer 7. Center sill spacers 39 are similar to center sill spacers 30 but are employed in spaced pairs and have vertical flanges parallel with and opposed to the flanges of angles 120 125 130

36 which lie against the outer face of center sills 1 and also horizontal parallel flanges.

The next transverse underframe member encountered in proceeding toward the center of the car, is a floor beam 8^a, serving the same function as floor beams 8 but being modified to accommodate a supporting structure for the inner tank head blocks and will be described more in detail in connection with the description of these head blocks.

Center sills 1 and side sills 9 are provided with floor stringer supports. Those carried by the side sills 9 are angles 40, preferably co-extensive with the sills, and secured to the outer faces of the vertical webs thereof. The floor stringer supports borne by the center sills 1 are on the outer faces of the webs of said center sills, but, as indicated in dotted lines in Fig. 1, are short angle pieces 41 spaced along the center sills at suitable intervals and riveted thereto. Floor stringers 42 are supported upon the side sill stringer supports 40 and may have the same length as the side sills themselves, while floor stringers 43 are carried by the center sill floor stringer supports.

The floor boards 44 are nailed to said stringers, and, as shown in Fig. 3, extend from one outside stringer 42 to that on the opposite side of the car, resting upon the stringers which derive their support from center sills 1. Extending transversely of said floor boards 44 and longitudinally of the car are timbers 45 of substantial cross section, these timbers being arranged in co-operating pairs, preferably in each half of the car, and each pair forming a tank bed. Cross tie rods 46, best seen in Figs. 2 and 3, maintain the transverse relationship between the timbers 45 of each pair of co-operating tank bed timbers and each timber has its upper surface curved or otherwise shaped to adjust itself to the curvature of the tank sheets 47. As indicated in Fig. 1, the tank sheets 47 each comprises a comparatively short cylinder, having annular flanges delineating the perimeter of the circular bases. Said flanges of adjoining tank sheets are secured together either by rivets or bolts and the end flanges of the end tank sheets of an accumulated series of said cylinders, form attachment means for tank heads 48 which may also be riveted or bolted into place. With this type of tank it is apparent that tanks may be quickly and easily assembled to suit the length of any car in which it is desired to install them. Also similar tanks may be assembled in desired lengths and arranged in any convenient series within a car of the type herein disclosed.

Adjustable head blocks are provided for each outer tank end and each comprises a rugged casting 49, having a base 50 and a crescent shaped pocket portion 51, being con-

nected therewith by an upright wall 52, shaped to hold pocket portion 51 at the desired height and position. The base and pocket portions are also connected by strengthening ribs 53 which strongly reinforce the pocket portion 51 when the latter receives an end thrust from the tank. Such end thrust, preferably, is not immediately received by the metal forming the pocket 51, the impingement of the tank head 48 being against a wooden block 54 retained by angle 55. The wooden block 54 and its retaining angle 55, are conformed to the crescent shaped pocket portion 51 of the tank head block casting and are so fitted thereto as to be slidable to a greater or less extent either farther into or out of said pocket, whereby the blocks 54 at opposite ends of the tank, may be adjusted to the length of such tank. The adjustment of blocks 54 is conveniently and reliably made by a plurality of wedge keys 56 in each tank head block, one of said wedge keys being shown in Fig. 5 to extend through slots of greater width than itself in the upper and lower walls of pocket portion 51 of the head block casting. Said key has an inclined surface that bears against an inclined face 57 in the top wall of the pocket portion 51 and against another inclined face 58 which constitutes the edge of a wall intermediate, but parallel with the upper and lower walls of said pocket 51. The lower end of key 56 is made cylindrical, as shown at 59 in Fig. 5, said cylindrical portion extending through the slot in the lower wall of pocket 51 and being provided with adjustment nuts 60, the inner one of which bears against a suitable washer lying against the lower wall of said pocket 51. It is clear from the construction shown in Fig. 5 that, by adjusting nuts 60 in the proper direction, key 56 may be moved either farther inwardly into or outwardly from said pocket portion 51, and that, when so moved the angle 55 which retains the wooden or other block 54 may be correspondingly moved into or out of the pocket in a direction parallel to the longitudinal axis of the tank. Thus adjustment of the head blocks to the tank heads is easily made with no more difficulty than is required by the ordinary application of a wrench.

The flanges at the joints of the cylindrical tank sheets 47 occupy the depressed portions of pressed metal channel members 61, which are inset in the upper or curved surface of said tank bed timbers 45. Such insertion of the flanges of tank sheets 47 into the grooves of channel members 61 serves to restrain the tank from longitudinal movement in either direction and prevents the total force of an end thrust being delivered immediately to any one of the tank head blocks. Channel members 61, therefore, also operate as a series of longitudinally spaced un-

yielding tank anchors arranged on both sides of the vertical center line of the tank. It is obvious that channel members 61 could be omitted and the grooves in the tank bed timbers 45 could be of less width, whereby the flanges of tank sheets 47 would be adapted to coöperate directly with the walls of said grooves. This, however, would subject the wood fibers of such walls to undesirable attrition, and it is considered preferable to insert the unyielding metal channel members 61 to protect the walls of the grooves in tank bed timbers 45.

The underframe is given a trussed construction which adequately supports the weight of the tank or tanks and their loadings. Truss rods 62 are arranged in substantially parallel pairs on opposite sides of the transverse center of the car. One end of each 20 of said rods passes through a cylindrical socket 63 integral with the base 50 of the tank head block casting at one end of the car. Extending toward the car center, each 25 of said truss rods 62 lies in a semi-cylindrical seat of a truss rod saddle, one such saddle being provided for each pair of parallel truss rods 62, and each saddle being secured to the upper surface of the bolster 6, or, more precisely, each is mounted on the upper surface 30 of the top cover plate 17 of the bolster 6. As shown in Fig. 1, truss rods 62 are deflected downwardly after passing through their 35 saddles 64, and continue in an oblique direction until they encounter semi-cylindrical seats in the strut casting 65, from whence the truss rods 62 continue in a horizontal direction to substantially the longitudinal center of the car. The truss rods 62 are here severed and the opposing ends thereof are 40 threaded to receive an adjusting turnbuckle 66. Only one half of the car has been shown, but it will suffice to say that, in extending to the opposite end of the car, the truss rods are reversely bent and in reverse order are 45 seated against a similar strut 65 and in similar truss rod saddles 64 on top of the bolster at that end of the car, continuing to the head block at that end, where they are secured in exactly the same manner as that shown in the 50 illustrated car end. Truss rods 62 are not only adjustable by the turnbuckles 66, but have their opposite ends protrude from the cylindrical sockets 63 of the head block casting, said truss rod ends being threaded to receive adjusting nuts 67.

The base 50 of the head block casting at each end of the car is mounted upon a supporting plate or platform 68, which has an upturned flange 69^a riveted to the web of the end sill 2, said platform extending under base plate 50 of the head block. Supporting plate or platform 68 has its rear corner portions mounted upon the diagonal braces 24, and, as said supporting plate 68 rests upon the draft sills 3, it is firmly and

solidly retained in place and is well adapted to support the head block at the end of the car.

In cars of the type illustrated, in which more than one tank is housed, inner head blocks, each provided with a base 50^a, are employed. Base 50^a is principally different from base 50 in that the cylindrical sockets 63 are not present and the head blocks containing the base 50^a are for the inner ends 70 of the tanks. The remainder of the construction is similar to the other head blocks previously described and corresponding numerals are applied to the corresponding parts.

The base plates 50^a of the inner head blocks are mounted upon the top cover plate 69 of the center sills 1 and also upon fillers 86 lying upon the upper surfaces of the top flanges of intermediate sills 70, which fillers 85 are co-extensive with the width of the base 50^a. The comparatively short intermediate sills 70 extend between cross bearers 7 (only one of which is shown), and pass through floor beam 8^a, as shown in Fig. 4. Floor beam 8^a is provided with top and bottom chords 26^a and 27^a, respectively, riveted to the upper and lower edges of floor beam web 25^a. Connection angles 29^a connect web 25^a to the side sill 9, and connection angles 95 28^a connect said web 25^a to the web of intermediate sills 70. A diaphragm 71 is connected to the opposite face of intermediate sill 70 and to the center sill 1. Top and bottom cover plates 31^a and 32^a, respectively, 100 extend across the top and bottom flanges of the top and bottom chords 26^a and 27^a, the upper and lower flanges of intermediate sill 70 and of diaphragm 71, and also the upper and lower flanges of the center sills 1, continuing in like manner to a corresponding point at the opposite side of floor beam 8^a.

Center sill supported stringers 43 are interrupted by the interposition of the tank head blocks having the base plates 50^a, but short stringers 72 are supported by angles 73 secured to the outer faces of the short intermediate sills 70 within the longitudinal limits of the interruption of the center sill supported floor stringers 43.

The floor boards 44 may, preferably, be fitted about the base plate 50^a of each of the inner head block castings and be properly supported while leaving an appropriate open area for the occupancy of said base plate 50^a. Short intermediate sills 70 each have their end portions secured to the web plates 33 of the cross bearers 7 and, therefore, each derives its support from said cross bearers and from the floor beam 8^a through which it 125 passes and forms a part.

Cross bearer 7 was said to be provided with angles 36, the lower ends of which were deflected outwardly as they extended below the center sills 1, and between the de- 130

flected portions of said angles 36 of each cross bearer is positioned the strut casting 65, flanges 74 of the strut casting 65 being secured to the contacting flanges of angles 36. Each entire cross bearer and the strut casting embraced thereby, therefore, becomes a strut adapted to act as a king or queen post. The truss rods become tension members of the truss and the draft sills and 10 center sills connected therewith become compression members of the truss, said truss giving ample support to the tank and its lading. Any tendency of the center sills to buckle upwardly will be resisted by the 15 weight of the tank or tanks mounted in the car, the structure illustrated being a well-balanced one so far as the resistance to buckling stresses is concerned.

The tank is also maintained in position by 20 the tank bands indicated at 75 in Fig. 3, which are secured at their lower ends to adjusting rods 76. The lower ends of said rods extend through a fixedly positioned casting 84 and are provided with adjusting 25 nuts 85; whereby the tension of tank bands 75 may be regulated. The tank is also stayed or anchored by adjusting rods 77, the lower ends of which pass through castings 78 mounted on the bottom chords 35 of the 30 cross bearer 7, or other members, adjusting bolts 79 being threaded on to the ends of said rods 77. The upper ends of rods 77 are secured by pins or other suitable means to connection plates 80 which are bolted to the 35 flanges of the cylindrical tank sections or sheets 47.

The usual inlet for the tank will, of course, be provided, though it is not shown, and the outlet may consist of the piping 81 is 40 shown in Figs. 1 and 3 to best advantage. Conveniently included in the piping 81 is an outlet valve 82 and the end of the outlet piping may be closed by a cap 83.

The outer superstructure of the car may 45 correspond to that of any approved box car, and, in the drawings, has been shown to comprise outer and inner side walls 87 and 88, respectively, and end walls 89 and 90 of similar construction. The usual car side 50 and end framing, it is understood, may, of course, be present and the car will be provided with a suitable roof (not shown).

Regarding the cross bearers 7, it is to be noted that the member 65 is provided with 55 a pair of truss rod seats on each side of the center line of the car. The inner seat of each pair is provided with a reinforcing rib 91 and the outer seat being extended to form another seat 92 adapted to receive the 60 lower corner of one of those cross bearer elements which contains the bottom chord 35 and angle 36.

What I claim is:—

1. In combination in a tank car, longitudinal central sills, forming compression

members of a truss, spaced tank head blocks mounted thereon, tension truss members anchored to said head blocks and struts between said compression members and tension members.

2. In combination in a tank car, longitudinal central sills forming truss compression members, a tank bed supported from said sills, a tank, spaced tank head blocks mounted on said sills, tension truss members anchored to said head blocks and struts between said compression and tension members.

3. In combination in a tank car, longitudinal car sills, a tank positioned thereabove, tank head blocks mounted on said sills, a tank, tension members anchored to said head blocks and cross bearers connected with said sills, extending between the latter and said tension members and serving as struts.

4. In combination in a tank car, longitudinal and transverse underframe members, a tank and tank head blocks mounted above said longitudinal members and tension members anchored to said head blocks, some of said transverse underframe members serving as struts between some of said longitudinal underframe members and said tension members.

5. In combination in a tank car, an underframe containing a truss provided with tension members, a tank supported thereby and tank head blocks, said tension members being anchored in said head blocks.

6. In combination in a tank car, an underframe containing a truss provided with tension members, a tank supported thereby and adjustable tank head blocks in which said tension members are anchored.

7. In a tank car, an adjustable tank head block comprising a member provided with a pocket and a base, a compression block and a retainer therefor both being slidable rearwardly and forwardly in the pocket and means operable between said retainer and the metal of the pocket for regulating the position of said block.

8. In a tank car, an adjustable tank head block comprising a fixed member containing a pocket, a slidable block in said pocket projecting therefrom, a retainer for said block and slidable therewith and means interposed between said retainer and the metal of the pocket and operable transversely of said block to position the latter.

9. In a tank car, an adjustable tank head block comprising a base member containing a pocket, a slidable block in the pocket projecting therefrom, and a wedge extending through said pocket and movable upwardly and downwardly to position said block with relation to said pocket.

10. In a tank car, an adjustable tank head block comprising a base member containing

- a pocket, a slidable block in the pocket projecting therefrom, a wedge extending into said pocket and movable upwardly and downwardly to position said block and adjustable locking means for said wedge.
11. In combination in a tank car, an underframe, a tank supported therefrom and an adjustable tank head block comprising a portion having rigid connection with said underframe and containing a pocket, a movable block seated in said pocket and means movable transversely thereof for advancing said block toward said tank.
12. In combination in a tank car, a tank provided with a head, an adjustable tank head block containing a pocket, a movable tank head-engaging member seated in said pocket and an adjustable key adapted to retain said head-engaging member in more than one position.
13. In combination in a tank car, central longitudinal sills forming truss compression members, bolsters and other transverse underframe members, a tank mounted above said sills, tank head blocks, saddles on said bolsters and truss tension members anchored to said head blocks, seated in said saddles and engaging some of said transverse underframe members.
14. In combination in a tank car, a suitably supported tank bed having a groove therein, a channel member of unyielding material seated in said groove, and a tank comprising sections meeting and forming a flange adapted to project into said channeled member to anchor said tank.
15. In combination in a tank car, a tank provided with a series of spaced flanges, a tank bed having a corresponding series of grooves and pressed metal channeled members seated in said grooves with which said flanges interlock to anchor said tank.
16. In combination in a tank car, a tank provided with a series of spaced circumferential flanges, and a tank bed comprising longitudinal members arranged on opposite sides of said tank and having correspondingly spaced grooves with which said tank flanges interlock and means for maintaining said longitudinal members in operative relation to the tank.
17. In combination in a tank car, longitudinally extending sills, floor stringers supported thereby, a floor resting on said stringers, a suitably retained tank supported from the floor, and tank head blocks extending below said floor and supported by said sills.
18. In combination in a tank car, an underframe comprising central and side longitudinal sills, transverse members and sills intermediate said central and side sills, said intermediate sills being secured to a plurality of said transverse members and passing through others thereof, a tank head block supported by said central and intermediate sills and a tank.
19. In combination in a tank car, an underframe comprising central and side longitudinal sills, transverse members and sills intermediate said central and side sills, each intermediate sill passing through and forming part of one of said transverse members and being secured to others thereof, a tank head block supported by said central and intermediate sills and a tank.
20. In combination in a railway car, central longitudinal sills, shorter longitudinal sills outside the central sills, a tank positioned above the longitudinal sills, a tank head block mounted on said sills, floor stringers supported by the central sills and having intermittent portions, floor stringers supported by said shorter sills opposing the space between the intermittent portions of the first mentioned stringers, and a floor supported by said stringers.
- In witness whereof I have hereunto set my hand in the presence of two witnesses.
